UNITED STATES PATENT OFFICE.

CHARLES H. COHN, OF NEW YORK, N. Y.

COMBINATION-LOCK.

No. 910,174.

Specification of Letters Patent.

Patented Jan. 19, 1909.

Application filed June 19, 1908. Serial No. 439,330.

To all whom it may concern:

Be it known that I, CHARLES H. COHN, a citizen of the United States, and a resident of the city of New York, borough of Manhattan, in the county and State of New York, have invented a new and Improved Combination-Lock, of which the following is a full, clear, and exact description.

This invention relates to combination locks.

10 An object of this invention is to produce a lock of this class which shall be of simple construction which can be readily operated by throwing the bolt, and having improved means for holding the bolt in its locked or 15 unlocked position.

A further object of the invention is to construct the parts in such a way that the case of the lock containing the lock mechanism, may be readily removed and replaced in 20 position and in connection with the operating members of the knob which controls the operation of the lock.

The invention consists in the construction and combination of parts to be more fully 25 described hereinafter and particularly set forth in the claims.

Reference is to be had to the accompanying drawings forming a part of this specification in which similar characters of reference indicate corresponding parts in all the figures.

Figure 1 is a side elevation of a lock, the inner covering being removed and certain parts being shown in cross section, this view 35 showing the bolt in its locking position; Fig. 2 is a view similar to Fig. 1, but showing the bolt in its withdrawn or unlocked position; Fig. 3 is a cross section through the lock, taken on the line 3—3 of Fig. 6, 40 that is, this section is taken at the inner side of the case looking outward; Fig. 4 is an elevation of the lock showing the lock case, and illustrating the manner in which it may be connected with the operating knob; Fig. 45 5 is a side elevation of the knob plate, and also showing the keeper and the manner in which the bolt coöperates therewith; Fig. 6 is a vertical section through the lock and door to which it is applied; Fig. 7 is a side 50 elevation of the tumbler shaft and showing the tumblers; Fig. 8 is a side elevation of one of the tumblers; Fig. 9 is a side elevation of another tumbler; and Fig. 10 is a fragmentary section on the line 10—10 of 55 Fig. 1, showing a detent spring which holds

the tumblers in different positions in which they are placed.

Referring more particularly to the parts, and especially to Figs. 1 to 3, and Fig. 6, 1 represents the case of the lock which is in 60 the form of a box, applied to the inner side of the door 2. This case is provided with a cover plate 3 seating on lugs 4 which are illustrated in Fig. 2. Within the case 1, a tumbler shaft or arbor 5 is rotatably 65 mounted, one end of the said shaft being received in a recess 6 in the wall of the case, while the other end is received in an opening 7 in the cover plate 3.

Referring now to Fig. 7, on the arbor 5, 70 there is provided a rigid tumbler or main tumbler 8, which is disposed adjacent the door 2; near the other end of the tumbler arbor a star wheel 9 is rigidly attached. From the face of the main tumbler 8, a dog 75 10 projects toward the star wheel 9, and this dog passes through circumferential slots 11 and 11^a which are formed in the movable tumblers 12 and 13. These tumblers are loosely mounted on the arbor between the 80 main tumbler 8 and the star wheel 9, as indicated by the dotted lines in Fig. 7. On the side of the case at a suitable point, a detent 85 spring 14 is attached, and this spring is split so as to form two fingers 15 and 16, as shown in Fig. 10. These fingers engage the edges 90 of the tumblers, as indicated in Fig. 2, so as to hold the tumblers in the position in which they are set in opening the lock. On the tumbler arbor, a collar 17 is rotatably 95 mounted between the main tumbler 8 and the cover plate 3, and this collar is provided with a driving toe 18 and a lock toe 19. The inner end of the arbor 5 is provided with a diametrically disposed slot 20, as indicated in Fig. 7.

In axial alinement with the arbor 5, I provide a knob or thumb head 21, which is the handle of a tubular stem 23 to which it is rigidly attached through the medium of a 100 reduced neck 22. This stem extends inwardly to the inner face of the door, and is provided with a diametrically disposed cross bar 24, as indicated in Fig. 5. Rotatably mounted on the stem 23, I provide a sleeve 105 25, which is rotatably mounted in an escutcheon 26, which is attached to the outer side of the door. On the inner end of this sleeve 25, a ring 27 is attached, said ring being provided with a shoulder 28 which is 110

countersunk into a knob plate 29, the said knob plate being countersunk on the inner face of the door, as shown. Beyond this shoulder 28, the ring 27 is provided with a 5 dog 30 which projects into the interior of the case through a slot 31 (see Fig. 4), formed in the cover plate. This dog 30 is adapted to engage the driving toe 18 so as to rotate the collar 17 by means of the knob 10 21, when the bolt is being withdrawn.

As shown in Fig. 6, the inner end of the stem 23 is enlarged so as to form a collar 32, and between this collar and the end of the sleeve 25, a space is left which allows a limited sliding movement of the stem within the sleeve, as will be readily understood. The sleeve 25 extends out to the inner face of the knob 21, and is provided with lugs 33 which project outwardly, as shown, and 15 these lugs are adapted to be engaged by stop pins 34 which project inwardly from the inner face of the knob. These pins 34 are quite short so that if the stem is pulled outwardly by means of the knob, the pins 34 20 will clear the lugs 33 so that the knob may be rotated without rotating the sleeve. Contrariwise, if the knob 21 is in the position shown, the pins 34 will engage the lugs and prevent the rotation of the stem without rotating the sleeve. As indicated, the edges of all the tumblers are provided with inclined notches or slots 35.

Referring now especially to Fig. 2, in the lower part of the case, a bolt 36 is pivotally 35 mounted on a pivot stud 37, the ends of which stud are rotatably mounted in the cover plate 3 and the wall of the case, as shown in Fig. 6. This bolt projects through a bolt opening 38 in the side wall of the case, 40 and this opening is elongated so as to permit the bolt to rotate on its pivot, as will be readily understood. From the upper edge of the bolt 36, an inclined spur or wing 39 extends upwardly, and near this spur, a finger 40 projects vertically. This finger is adapted to be engaged by the lock toe 19 so as to rotate the bolt on the pivot 37, as indicated in Fig. 2. This rotation can only take place when all of the notches 35 of the 45 tumblers are in alinement, as indicated in Fig. 2. From the upper edge of the bolt a guard finger 41 extends upwardly, and this guard finger closes the upper part of the bolt opening when the bolt is in its locked 50 or horizontal position, as indicated in Fig. 5. The bolt is normally constrained toward its locking position by means of a leaf spring 42 which is attached to a fixed stud 43 on the cover plate. This spring thrusts against a 55 pin 44 on the side of the bolt, as indicated.

In order to cause the arbor 5 to advance by a step-by-step movement, I provide a detent spring 45 which co-operates with the star wheel 9. As indicated in Fig. 3, this 60 spring is mounted in a fixed post 46 and pro-

jects radially toward the axis of the arbor. This spring is straight and engages, as shown, in the notches between the teeth of the star wheel 9. Evidently this spring will tend to arrest the star wheel in the position shown, 70 that is, with one of the notches between its teeth disposed at the spring. On the lower edge of the bolt, a short horizontal tongue 47 is provided, and opposite to this tongue, a button 48 is rotatably mounted in the wall 75 of the case. This button has a wing head 49 for rotating the same on the outside of the case, and on the inside of the case an enlarged head 50 is formed. This head is of oblong form, as shown in Fig. 3, and provided near one edge with a short locking stud 51 which projects toward the bolt. On the opposite edge, a long stud or unlocking stud 52 is provided, which projects under the bolt, as indicated. When the bolt is in its 80 locking position as indicated in Fig. 3, this button 48 may be rotated so as to bring the locking stud 51 over the tongue 47, as shown. The stud then lies in the path of the tongue and prevents the bolt from being moved upwardly. In this way the lock may be fastened from the inside so that it cannot be unlocked from the outside even by using the combination. If, however, the button 48 is rotated into the opposite position, as indicated in Fig. 2, the unlocking stud 52 will engage the lower edge of the bolt and lie in the path of the bolt so as to prevent its being returned to its locking position. Evidently, 85 if the combination has been set on the tumblers, this button 48 may be used to throw the bolt from the inside, the bolt then rotating simply as an ordinary latch.

In the wall of the case 1, a stop pin 53 is mounted. This pin is encircled by a spring 105 54 which seats against the wall of the case and thrusts against a collar 55 and tends to hold the pin with its inner end projecting into the interior of the case and into the path of the teeth of the star wheel. On the 110 exterior of the case, the stem 53 is provided with a wing head 56 which enables it to be withdrawn, and this wing head is provided with nibs 57 on its inner edge, which are adapted to engage with the outer face of a 115 boss 58 when the stem is rotated to a small angle. In this way the nibs 57 will hold the stem in a slightly withdrawn position so that its inner end will clear the star wheel.

Referring to Fig. 5, the bolt 36 is adapted 120 to co-operate with a keeper 59, the said keeper being attached to the face of the jamb 60, as shown. The upper part of the keeper has a notch 61 through which the bolt may pass when in its elongated or inclined position. 125 When the bolt drops down to its horizontal position, it passes behind the lip or flange 62 of the keeper so that it locks the door against being opened, as will be readily understood. On the outer side of the knob 130

21, at a suitable point, a mark or projection 63 is provided, which indicates the position of the cross bar 24. This projection is useful in indicating the point from which the 5 rotation of the knob will begin in applying the combination of the lock.

The mode of operation of the lock will now be described: By rotating the knob 21 from a certain definite position indicated by 10 the projection 63, the rotation of the knob is imparted to the arbor 5. The dog 10 will then advance the tumbler 13 in the longest slot 11^a to the proper position determined by the combination. The amount of advance 15 which has been given to this tumbler is indicated constantly by the clicking of the spring 45 over the teeth of the star wheel. The next tumbler 12 being set over to the proper position by an opposite rotation of 20 the knob, the knob is then rotated back to the proper position to bring the notch of the main tumbler 8 in alinement with the other notches of the tumblers. It should be understood that before rotating the knob 25 to set the combination, it is necessary to pull it out slightly so as to remove the path of the pins 34 from the lugs 33. This of course permits the free rotation of the stem independently of the sleeve 25. After the 30 combination has been set as suggested, the knob 21 is pushed inwardly so that when rotated the pins 34 will engage the lugs 33 and rotate the sleeve. The sleeve is then rotated in the proper direction so that the 35 dog 30 will engage the toe 18 and advance the same toward the right, as indicated in Fig. 2. This rotates the collar 17 and advances the toe 19 against the finger 40 of the bolt. This rotates the bolt upwardly on 40 its pivot, and this rotation is permitted by reason of the fact that the slots 35 will all be in alinement opposite to the spur 39, so that the spur 39 can pass upwardly into the slots, as indicated. As shown in Fig. 1, 45 the end of the spur 39 lies close to the edges of the tumblers, so that if the slots 35 are not alining, as suggested, the bolt cannot be thrown upwardly. After the bolt has been drawn to its unlocked position it may be 50 secured by the button 48 as described above. A person on the interior may set the stop pin 53 so that it coöperates with the star wheel 9, so as to prevent the opening of the lock from the exterior even by use of the 55 combination.

In pulling the knob 21 outwardly, it should be understood that the bar 24 slides outwardly in the slot 20, but does not become removed from the slot. In this connection 60 attention is called to Fig. 6, wherein the end of the tumbler shaft is represented as projecting into the inner end of the tubular stem 23. In this way a sliding connection between the stem and the shaft is effected, 65 but the rotation of the stem is always com-

municated to the tumbler shaft. For this reason it should be understood that in the unlocking movement of the bolt, the tumblers also rotate. This rotation of the tumblers is made possible by forming the inner 70 ends of the slots 35 with enlargements 35^a. These enlargements form clearance for the inner end of the spur or wing 39.

Having thus described my invention, I claim as new and desire to secure by Letters 75 Patent,—

1. In a combination lock, a case, a tumbler shaft rotatably mounted in said case, a plurality of tumblers carried thereby, a knob, means actuated by said knob to set said 80 tumblers, a pivoted bolt projecting from said case and normally held against rotation by said tumblers, and a rotatable member actuated by said knob after said tumblers are set to the combination, said rotatable 85 member having a projecting toe engaging said bolt to actuate the same.

2. In a combination lock, a case, a tumbler shaft mounted therein, a plurality of tumblers carried thereby, a knob, means actuated 90 by said knob for advancing said tumblers to set the combination of the lock, a pivoted bolt projecting from said case and normally held against rotation by said tumblers, a loose collar on said tumbler shaft, means for 95 actuating said collar by said knob after the combination is set, and a member carried by said bolt adapted to be engaged by a part of said collar to throw said bolt.

3. In a combination lock, a case, a tumbler 100 shaft rotatably mounted therein, a plurality of tumblers carried by said tumbler shaft, a knob, means actuated thereby for rotating said tumbler shaft to set said tumblers to the combination, a pivoted bolt normally 105 locked against movement by said tumblers, means for rotating said bolt on its pivot operated by said knob when the combination is set, and means whereby the rotation of said knob in actuating said bolt rotates 110 said tumblers.

4. In a combination lock, a case, a tumbler shaft mounted in said case, a plurality of tumblers mounted upon said tumbler shaft, a knob having a stem having a sliding connection with said tumbler shaft and adapted to rotate the same, a bolt, means for actuating said bolt by a rotation of said knob when in its innermost position, and means for setting said tumblers by said knob when 115 120 in its withdrawn position.

5. In a combination lock, a case, a tumbler shaft rotatably mounted therein, a plurality of tumblers mounted on said shaft and having notches in the edges thereof adapted to 125 be alined, a knob, means actuated by said knob for setting said tumblers to the combination, a pivoted bolt having a spur lying opposite to said notches when the combination is set, and a projecting member inde- 130

pendent of said tumblers for rotating said bolt, engaging said bolt and actuated by said knob after the combination is set.

6. In a combination lock, a case, a tumbler shaft rotatably mounted therein, a stem having a sliding connection with said tumbler shaft and adapted to rotate the same, a plurality of tumblers carried by said tumbler shaft, a loose sleeve on said stem, means whereby the stem may rotate said sleeve, a pivoted bolt having a spur lying near the edges of said tumblers and normally locked against movement, said tumblers having notches adapted to aline with said spur when the combination is set, and means actuated by said sleeve for moving said bolt.

7. In a combination lock, a case, a tumbler shaft rotatably mounted therein and having a slot in the inner end thereof, a plurality of tumblers mounted on said tumbler shaft, a rotatable stem having a cross bar disposed in said slot whereby said stem may be moved relatively to said shaft and rotate the same, a sleeve on said stem adapted to engage with said stem to be rotated by said stem when said stem is in its innermost position, said stem being adapted to be disengaged from said sleeve when drawn outwardly, a pivoted bolt normally locked by said tumblers, said tumblers releasing said bolt when set to the combination, and means for actuating said bolt by said sleeve.

8. In a combination lock, a case, a tumbler shaft rotatably mounted therein, a plurality of tumblers mounted upon said shaft, a rotatable stem having sliding engagement with said shaft and adapted to rotate the same, a sleeve which may rotate free around said stem, means whereby said stem may engage with said sleeve to rotate the same, a collar on said shaft, a dog carried by said sleeve engaging said collar to rotate the same, a bolt normally locked and released by said tumblers when said tumblers are set to the combination, and means for actuating said bolt from said collar.

9. In a combination lock, a case, a tumbler shaft rotatably mounted therein, a plurality of tumblers mounted upon said shaft, a rotatable stem having sliding engagement with said shaft and adapted to rotate the same, a sleeve loose around said stem, means

whereby said stem may engage with said sleeve and rotate the same, a collar on said shaft, a dog carried by said sleeve engaging said collar to rotate the same, a bolt normally locked by said tumblers and released only when said tumblers are set to the combination, means for actuating said bolt from said collar, and a cover plate for said case, said cover plate having a slot therein through which said dog projects.

10. In a combination lock, a case, a tumbler shaft rotatably mounted therein, a plurality of tumblers mounted upon said shaft, a rotatable stem having sliding engagement with said shaft and adapted to rotate the same, a sleeve loose around said stem, means whereby said stem may engage with said sleeve and rotate the same, a collar on said shaft, a dog carried by said sleeve engaging said collar to rotate the same, a bolt adapted to open only when said tumblers are set to the combination, means for actuating said bolt from said collar, and a cover plate for said case, said cover plate having a slot therein through which said dog projects, said case and said cover plate affording means for supporting said shaft.

11. In a lock, a pivoted bolt, means for rotating said bolt on the pivot thereof, and a rotatable button having a locking stud adapted to engage said bolt to hold the same in its locked position, said button having an unlocking stud adapted to engage said bolt to hold the same in its unlocked position.

12. In a lock, a bolt mounted upon a pivot, means for actuating said bolt, said bolt having a tongue on the side thereof, and a rotatable button having a locking stud adapted to project over said tongue in one position of said button to hold said bolt in its locked position, said button further having an unlocking stud projecting under said bolt and adapted to hold the same in its unlocked position.

In testimony whereof I have signed my name to this specification in the presence of two subscribing witnesses.
